UNITED STATES PATENT OFFICE.

JOHN V. RICE, JR., OF BORDENTOWN, NEW JERSEY, ASSIGNEE, BY MESNE ASSIGNMENTS, TO FRED E. TASKER, OF NEW YORK, N. Y.

FLUID-PRESSURE STARTER FOR GASOLINE DRILLS.

Application filed August 28, 1920, Serial No. 406,725. Renewed May 24, 1927.

This invention relates to a fluid pressure starting mechanism for a rock drill, more particularly a gasoline rock drill, or one that is actuated by the explosions of an explosive mixture in an internal combustion engine; and said mechanism is pneumatically operated to obtain the best and quickest results in the easiest way. The object of the invention is to provide a simple auxiliary means as an aid in the starting and handling of explosion drills. The invention therefore consists essentially in the construction, arrangement and combination of parts, substantially as will be hereinafter described and claimed.

In the annexed drawing illustrating my invention:

Figure 1 is a longitudinal section of a half portion of a gas-actuated rock drill, the same being shown provided with part of my present improved pneumatic starting mechanism.

Figure 2 is an outside elevation of an entire gas-actuated drill of this kind and is represented as fully equipped with my improved device.

Figure 3 is a cross-section on the line 3, 3, of Figure 2.

Figure 4 is a cross-sectional view on the line 4, 4, of Figure 1.

Similar characters of reference designate corresponding parts throughout all the figures of the drawing.

While it will at once be manifest that the present invention in various forms is applicable to various designs and kinds of drills, yet it is particularly adapted and intended for use with the gasoline rock drill described and claimed in my former United States

Letters Patent, dated August 6, 1907, No. 862,847, and my other similar drilling appliances, wherein the motive power is derived from the explosion of a gaseous mixture. It will be unnecessary to recapitulate or

illustrate the entire mechanism of the aforesaid patented drill of mine, in order to explain the present invention, for it will suffice to point out a few of the leading mechanical and operative elements shown in the views, 1 being the cylinder or main frame, 2 the feed screw, 4 one of the end portions of the free trunk piston, which has a duplicate (not shown) at the other end of the frame, 3 the interior connecting rod between the trunk sections of the piston, 5 the power

transmitting element or drilling implement which is actuated by the movements of the free piston, 6 the drill chuck, 7 the explosion chamber in one end of the machine, its counterpart (not shown) being in the other end also, 8 the water-jacket, and 9 an oiling device for introducing oil to the surface of the piston. The engine has of course the usual gas engine accessories, for ignition, inlet and exhaust, timing, lubrication, etc., but it is unnecessary to describe them at this time, as they form no part of the present invention, and may be varied within wide limits.

Proceeding now to describe the construction and operation of my novel air-starting mechanism, it will be seen that the end of the cylinder 1, shown in Figure 1, that contains piston section 4, is provided with a head 10, screwed to the cylinder 1 or otherwise strongly secured thereto, there being a chamber 14 between the inner surface of the head 10 and the adjacent end of piston 4, which chamber is of variable size as the piston travels back and forth, and is adapted to receive air which is drawn thereinto by the action of piston 4. There is a central passage 45 running through the head 10, and at the end of this passage nearest the chamber 14 is arranged a valve 15 which functions in connection with an inclined seat 16, and whose stem 17 operates in a bearing 47, there being a spring 48 surrounding said bearing and tensioned between a shoulder on the same and a projection or collar 49 on the stem 17 so as to act as a closing spring for the valve 16. Said valve 16 therefore opens under the suction of the piston 4 and closes when the suction is relieved, and the spring 48 is allowed to pull the valve 16 shut.

Secured to the cylinder head 10 by means of screws 19, or other suitable means, is a supplemental head 11 consisting of a hollow casting having a central opening 46 that coincides with the passage 45 in the head 10. The wall of chamber 18 within the casting 11 is pierced by a series of holes 43 which admit atmospheric air into said chamber. Further the chamber 18 is provided with a dome-shaped or convex cover 12, between which and chamber 18 is secured a flexible diaphragm of metal or other material 13 so as to form a second chamber 50 outside of and distinct from chamber 18.

This diaphragm 13 carries at its centre a rod or pin 20 that works through a skeleton

guide 22 supported on the inner wall of chamber 18 contiguous to and over the central opening 46; and pin 20 is in alignment with the end of valve stem 17 and adapted 5 to strike the end of same when the air or fluid pressure within the chamber 50 is sufficiently strong as to bend the flexible diaphragm 13 and cause the pin 20 to slide through bearing 22 and strike valve stem 17, 10 there being a spring 21 around pin 20 and tensioned between the fixed guide 22 and the centre of the diaphragm 13 so as to return the diaphragm to its normal position, or to assist it in so doing, after the air pressure 15 in chamber 50 is reduced. The effect of the contact of the end of pin 20 with the valve stem 17 will be to open, and so long as the contact is maintained under a constant pressure, to hold open the valve 15, so that 20 air may pass with a steady flow from the outer atmosphere through holes 43 into the interior of the drill cylinder 1, from which interior of the cylinder the air will pass to the storage tank 29 when the valve 15 is 25 closed as I shall explain.

The cylinder head 10 is further provided with another passage 42 leading to and from the chamber 14 within cylinder 1, in connection with which passage 42 is arranged a 30 check valve 26 that is closed by a spring 27 carried by a pin which forms part of a screw plug 28 that is inserted through the side wall of the head casting 10. This valve 26 opens on the outstroke of the piston 4 to force air pressure out of the chamber 14 by way of passage 42, and the valve closes under the action of spring 27 to prevent the return of such pressure when the opening pressure ceases to act upon it. The valve casing 51 35 which is formed on the wall of head 10 as shown in Figure 1, is only a continuation of passage 42, and is provided with a branch pipe 24, to which is connected a short tube 23 running to and through the side of the 40 cover 12 and into the chamber 50 on the outside of the diaphragm 13. The pipe 24 is preferably a T-union, or other suitably shaped pipe member, which connects with a pipe or passage 25 leading to a main pipe 45 line 30 which runs to a storage tank 29, see Figure 2.

This main line continues as pipe 32 along side of the frame of the drill and supplies air from the tank or storage under pressure 50 at each end of the piston in the engine cylinder, so that through valve devices to be presently explained the air or fluid pressure may be introduced into either of the chambers 7, so as to start the piston in one direction or the other, as may be and whenever desired. It will be clearly seen therefore that the piston of the gasoline engine or drill pumps air from the outer atmosphere and transmits it through suitable channels 55 into a storage tank. When this pressure in

said tank and against the diaphragm 13 is strong enough, it will open and keep the air-inlet valve 15 open all the time; and the action of the piston when the valve 15 is so open will merely cause air to flow in and out; but whenever the pressure drops through a use thereof the valve 26 will on the back stroke of the piston be opened to let fresh air enter the volume of the storage supply. The storage supply is thus made 70 use of whenever desired to start the engine and set the drill in operation. The tank 29 and the main line of piping 30 and 31 are full of air at high pressure ready for instant use. Said line is provided with a cock 31, 80 which serves to cut out the starting mechanism proper when the tank is being regularly charged, or otherwise to control the handling of the fluid pressure, when the starting valves are inactive for any reason. 85

The pipe 32 is provided with a pair of short branches 40 that are screwed into the wall of drill frame or cylinder 1, and each of these connects by a short inner tube 39 with a valve chamber wherein is a valve 35 that admits into one of the chambers 7 in the cylinder 1 and alongside the piston 4. Each valve 35 has a stem 41 that runs through a closed casing 52, having cap 33, and projects outside of said cap 33. Inside of casing 52 the stem 41 is provided with a spring 38 tensioned between the end of the casing and a collar or lug on the stem and serving as a closing spring for the valve 35. The cap 33 has a projection 37 in which is pivoted a valve-operating handle 34 formed with a lug or nose 36 which bears against the end of the valve stem 41 when the handle is lifted and thus forces the stem inwardly and unseats the valve, compressing spring 38 in so doing. When the handle 34 is allowed to drop again the spring 38 quickly reseats the valve. The opening of the valve in this manner permits air pressure to escape from the pipe system already described and pass into the cylinder 1, thus entering into one of the chambers 7 thereof, where it will act on the piston 4 and start the same. Either of the handles 34 is very easily operated by simply lifting with the finger, 100 as they are small and the action of the spring 105 will preferably be light and simple.

A short additional statement will cover anything that may be desirable to complete an understanding of the operation. Let us 110 assume that the tank 29 contains the necessary amount of compressed air or other fluid pressure for use in starting the piston, which pressure may have been created by the operation of the piston started in some other way, or may have been otherwise derived. The operation of the piston is like the action of a pump plunger, and the air is pumped into the tank in proportion as it is needed, the inlet valve being kept open as I have 115

explained when the tank is full. The operator by an easy manipulation of the levers 34 is able to inject segments of fluid pressure behind one or the other of the trunk sections 5 of the piston, which pressure will impart the power needed to start the movement of the piston and its connected drilling implement in one direction or the other, at any time, whenever the drill has been stopped 10 for any reason, or has been allowed to run irregularly. In this way it will be found that by the simple appliances described I provide starting impulses in the most economical and practical and certain way, with 15 all the conditions of success and satisfactory results, and thereby contribute substantially to the acceptable use of a gasoline rock drill mechanism, or any other similar organization of moving parts wherein the power is 20 derived from a reciprocating member, as a piston, actuated by explosions, which member it is necessary to start from time to time, or to reverse.

I have explained my invention as particularly adapted for certain uses, but I do not wish to be restricted thereto. I reserve the liberty of applying it for use wherever it is found serviceable. Also I claim the right to modify the details thereof, and change, 30 reconstruct and rearrange the relations of the parts, within wide limits, so as to secure the best results, provided this is done within the scope of the appended claims.

Having thus described my invention, what 35 I claim as new and desire to secure by Letters-Patent is:

1. In a fluid pressure starter for gasoline rock drills and the like motors, having a free piston, which acts as a pump plunger, the 40 combination with the piston, of a cylinder, a head on the latter having a central passage, axially in line with the central axis of the cylinder, a suction valve in said passage opening into the cylinder for admitting air 45 to the cylinder, a bearing in the passage supporting the valve stem together with a spring for closing the valve, a storage tank, means for carrying air pressure from the cylinder to the tank including a passage running 50 through the head and having a check valve, an auxiliary hollow chamber removably carried on said head, a flexible diaphragm dividing said chamber into two compartments, one of which nearest the head and communicating with the passage therein, has lateral 55 openings to receive air from the atmosphere, and the other of which communicates with the means for carrying air to the storage tank; means consisting of a spring-provided pin on the diaphragm adapted to loosely contact with the valve stem to hold the valve open when the storage pressure is of a predetermined degree, and a guide device on the wall of the chamber through which the pin 60 slides in contacting with the valve stem.

2. In a fluid pressure starter for gasoline rock drills and like percussion machinery, having a free piston, a member of which acts as a pump plunger, the combination with the piston and the cylinder, of a pipe line for conveying air pressure for use in starting, pressure chambers adjacent to the piston at points in the pipe line, a valve in each of said chambers for allowing air to pass therefrom to act against the piston, said valves 70 having projecting stems, pivoted handles having lugs engaging the ends of said valve stems, a cylinder head having a central passage, axially in line with the central axis of the cylinder, a suction valve in said passage 80 opening into the cylinder for admitting air to the cylinder, a bearing in the passage supporting the valve stem together with a spring for closing the valve, a storage tank, means for carrying air pressure from the cylinder to the tank including a passage running through the head and having a check valve, an auxiliary hollow chamber removably carried on said head, a flexible diaphragm 85 dividing said chamber into two compartments, one of which nearest the head and communicating with the passage therein, has lateral 90 openings to receive air from the atmosphere and the other of which communicates with the means for carrying air to the storage tank, means consisting of a spring-provided pin on the diaphragm adapted to loosely contact with the valve stem to hold the valve open when the storage pressure is of a predetermined degree, and a guide device on the wall of the chamber through which the pin 95 slides in contacting with the valve stem.

3. In a fluid pressure starter for gasoline rock drills and like percussion machines having a free piston, a member of which acts as a pump plunger, the combination with the piston and the cylinder of a pipe line for conveying the air pressure for use, chambers adjacent to the piston at each end of the drill receiving said pressure, a valve in each chamber for allowing air to pass therefrom to act against the piston, said valve having a stem, a casing forming a bearing for said stem, a spring within said casing to close the valve, and an external operating handle pivoted on the casing and having a lug engaging loosely the projecting end of the valve stem to open the valve, a cylinder head having a central passage, axially in line with the central axis of the cylinder, a suction 110 valve in said passage opening into the cylinder for admitting air to the cylinder, a bearing in the passage supporting the valve stem together with a spring for closing the valve, 115 a storage tank, means for carrying air pressure from the cylinder to the tank including a passage running through the head and having a check valve, an auxiliary hollow chamber removably carried on said head, a flexible diaphragm 120 dividing said chamber 125

4
into two compartments, one of which nearest the head and communicating with the passage therein, has lateral openings to receive air from the atmosphere and the other of which communicates with the means for carrying air to the storage tank, means consisting of a spring-provided pin on the diaphragm adapted to loosely contact with the

valve stem to hold the valve open when the storage pressure is of a predetermined degree, and a guide device on the wall of the chamber through which the pin slides in contacting with the valve stem. 10

In testimony whereof I hereunto affix my signature.

JOHN V. RICE, JR.
